(57) **CLAIM**

The ornamental design for casual sneaker, as shown and described.

DESCRIPTION

FIG. 1 is a perspective view of the casual sneaker according to an embodiment of our new design;

FIG. 2 is front view thereof;

FIG. 3 is a rear view thereof;

FIG. 4 is a left-side view thereof;

FIG. 5 is a right-side view thereof;

FIG. 6 is a top view thereof; and

FIG. 7 is a bottom view thereof.

FIG. 8 is a perspective view of a casual sneaker according to a first embodiment of our new design;

FIG. 9 is front view thereof;

FIG. 10 is a rear view thereof;

FIG. 11 is a left-side view thereof;

FIG. 12 is a right-side view thereof;

FIG. 13 is a top view thereof; and

FIG. 14 is a bottom view thereof.

FIG. 15 is a perspective view of the casual sneaker according to a second embodiment of our new design;

FIG. 16 is front view thereof;

FIG. 17 is a rear view thereof;

FIG. 18 is a left-side view thereof;

FIG. 19 is a right-side view thereof;

FIG. 20 is a top view thereof; and,

FIG. 21 is a bottom view thereof.

The broken lines shown herein are only for illustrative purposes of the environment and form no part of the claimed invention.
